UNITED STATES PATENT OFFICE.

FREDERICK W. MOLDEN, OF HURON, SOUTH DAKOTA.

VEHICLE-CURTAIN ATTACHMENT.

SPECIFICATION forming part of Letters Patent No. 699,967, dated May 13, 1902.

Application filed February 15, 1902. Serial No. 94,268. (No model.)

To all whom it may concern:

Be it known that I, FREDERICK W. MOLDEN, a citizen of the United States of America, residing at Huron, in the county of Beadle and State of South Dakota, have invented certain new and useful Improvements in Vehicle-Curtain Attachments, of which the following is a specification.

This invention relates to carriages and wagons, and particularly to curtains and aprons for excluding dust, rain, snow, or wind.

The object of the invention is to produce attachments which may be employed in connection with vehicle-bodies for closing the sides and the spaces between the dashboard and seat and the space between the seats.

Furthermore, the object of the invention is to produce attachments which may be adjusted to vehicles of varying configurations and sizes, thus making one set applicable for use in a plurality of vehicles.

Furthermore, the object of the invention is the production of an apron having waterproof pockets for containing papers or objects, said pockets being convenient to the occupants of the vehicle.

Finally, the object of the invention is to produce attachments of the foregoing described type which will possess advantages in points of simplicity, durability, and efficiency, proving at the same time comparatively inexpensive to produce and sustain.

With the foregoing and other objects in view the invention consists in the details of construction and in the arrangement and combination of parts to be hereinafter more fully set forth and claimed.

In describing the invention in detail reference will be had to the accompanying drawings, forming part of the specification, wherein like characters denote corresponding parts in the several views, and in which—

Figure 1 is a view in elevation of a vehicle-body of the surrey type with the invention applied. Fig. 2 is a view in elevation of one section of the attachment. Fig. 3 is an elevation of another adjustment of the parts. Fig. 4 is a view in elevation of a wagon-body with a hood-like apron. Fig. 5 is a sectional view taken longitudinally of Fig. 1.

In the drawings, 1 denotes a section of a

frame fitting the edges of a dashboard and having hook-shaped lugs 2, which hook over the dashboard at the top. The sections are provided with overlapping ends 3 and coinciding apertured lugs 4, which are connected by the bolt 5. The sections 1 have ends 6 bent at an angle to engage with an end 7 of the section 8 of the frames for the front seat. The section 8 has a depending portion 9, which is bent in and pivoted with a serrated flange 10 to engage the under surface of the body. An extension 11 has an angular end 12 attached to the angular end 13 of the section 8, and the extension 11 has arms 14 and 15, the former terminating in an outwardly-turned ear 16, which is apertured to receive the supporting-hook of an apron to be hereinafter described, and the arm 15 is provided with an inturned end 17, supported on the edge 70 of the seat. A bolt 18 is employed to bind the sections 8 and 11 together, and as the length of the bolts may be varied it is apparent that the sections of the frame may be adjusted within certain bounds and that by 75 proper adjustment the frame may be securely clamped in place.

The rear frame comprises an approximately vertical standard comprising an upper and lower section 19 and 20, the former having an 80 inturned end 21 to engage the front seat and the latter having foot 22, fitting under the vehicle-body. The sections 19 and 20 are connected by a bolt 23, run through their ends. The lower section 20 has an arm 23, with an 85 angular end 24 to coact with the angular end 25 of the extension 26, said extension 26 having arms 27 and 28 similar to the arms 14 and 15, before described. The front and rear frames have studs 29 to fit in eyes of a curtain or apron (not shown) which is to follow the contour of the frames to inclose the body.

In the disclosures of Figs. 4 and 5 I show a vehicle-body the front of which is inclosed by an apron A, with arms B terminating in 95 hooks C, which fit in apertures of a lug D. The hook C is the same as the one to be employed to engage the angular end 16 of the arm 14, as heretofore described. The apron A is secured to stud or button E by having 100 the said button run through eyes F of the apron.

Pockets 9 are secured on the under surface to contain papers and the like.

Having fully described my invention, what I desire to secure by Letters Patent is—

5 1. In an attachment for vehicle-curtains, a sectional frame extending along the top and ends of the dashboard, and along the side of the body, then diagonally upward, means on the section for engaging the edge of a seat, a member engaging the under surface of the body and means for clamping the sections together.

15 2. In an attachment for vehicle-curtains, a frame comprising an approximately vertical standard with an upper and lower section, the former having an inturned end to engage a seat, and the latter having a foot fitting under a body, an arm formed with the lower section, an extension bolted to the arm and mem-

bers carried by the arm for engaging the edge of a seat, as and for the purpose described.

3. In an attachment for vehicle-curtains, a frame comprising an approximately vertical standard with an upper and lower section, the former having an inturned end to engage a seat, and the latter having a foot fitting under a body, an arm formed with the lower section, an extension bolted to the arm and a member carried by the arm for engaging the edge of a seat and a second member for engaging a supporting-hook.

In testimony whereof I affix my signature, in the presence of two witnesses, this 6th day of February, 1902.

FREDERICK W. MOLDEN.
